UNITED STATES PATENT OFFICE.

EDMOND HÉROUX, OF YAMACHICHE, CANADA.

WINDOW-SASH.

SPECIFICATION forming part of Letters Patent No. 707,106, dated August 19, 1902.

Application filed February 28, 1902. Serial No. 96,051. (No model.)

To all whom it may concern:

Be it known that I, EDMOND HÉROUX, a subject of the King of Great Britain, residing at Yamachiche, county of St. Maurice, Province of Quebec, Canada, have invented certain new and useful Improvements in Window-Sash; and I do hereby declare that the following is a full, clear, and exact description of the invention, such as will enable others skilled in the art to which it appertains to make and use the same.

The improvement forming the subject of this invention consists in a peculiar construction of sash-casing in combination with certain attachments on the sash, which adapt the latter both to the sliding and casement forms; and the object of this invention is especially to provide for the easy cleaning of windows, especially the outer side of the glass, whereby the necessity of climbing outside the window for this purpose and the danger always incident thereto, as well as the discomfort of this proceeding in cold weather, are entirely avoided. The sash being formed by a proper manipulation to open inwardly on a hinge, as in the casement or French form, the cleaning of panes may be done entirely from the inside of the apartment, and, moreover, it may be done while standing on the floor and without the necessity of climbing upon the sill of the window.

Another object of this invention is to provide an easy manipulation for the sashes of windows, whereby the same are adapted to either form of opening, as may seem most desirable, and to enable the entire frame to be opened in cases where increased ventilation is desired or, if necessary, the entire sash, both upper and lower portions, to be removed without the necessity of any carpenter-work or removal of other parts.

My improvement embodies a form of sash which is mounted to slide in guides and between beads or sash-slides upon the interior wall of the casing, as in the ordinary form of sash; but the sash is provided at one side with depending pintles, which are adapted to engage when desired in suitable sockets carried on the corresponding sash slide or bead, while the slide or bead upon the opposite side of the casing is adapted to be pushed back out of the way, whereby to allow the

window-sash to be turned upon the hinge above mentioned and to open inwardly, while in the meantime the act of displacing the bead and of subsequently turning the sash on its hinge causes the weight-cord to become detached and to be locked in place between the slides of the casing in a suitable groove provided for it until such time as the window-sash is again closed, which act, together with the replacement of the bead, automatically causes the sash-cord to be reengaged with the sash and the weight to come into action to raise the same.

My improvement is applied not simply to the inner or lower sash of a window, but preferably, also, to both sashes, whereby they may be both opened simultaneously when desired.

My invention consists, moreover, in the peculiar construction and combination of parts hereinafter specifically set forth and more particularly pointed out in the claims.

I have illustrated the preferred form of my improved sash in the accompanying drawings, wherein—

Figure 1 is a perspective view of a window-casing having double-hung sashes embodying my improvement. Fig. 2 is an elevation of the inner side of the window-casing shown on the right of Fig. 1 and showing the head and sill of the window-frame in section. Fig. 3 is a vertical section taken at right angles to Fig. 2 and on the line 3 3 of Fig. 2. Fig. 4 is a transverse vertical section through the lower portion of the window looking toward the left of Fig. 1 and showing both sashes in position ready to open. Fig. 5 is a perspective view, on an enlarged scale, of the movable section of the sash bead or slide. Fig. 6 is a similar view of another portion of the sash-bead. Fig. 7 is an enlarged fragmentary perspective view showing one form of adjustable hinge for the sash. Fig. 8 is a similar view showing another form of hinge. Fig. 9 is a perspective detail of the attachment-piece for the sash-cord. Figs. 10 and 11 are enlarged fragmentary elevations of a portion of the casing, showing the action of the attachment-piece; and Fig. 12 is an enlarged detail showing a modified form of hinge-pintle.

The same numerals of reference denote like parts in all the figures of the drawings.

Referring to Fig. 1, the frame of the window is of the ordinary form for double-hung sashes and consists of a headpiece 13, a sill 14, and side pieces 15 and 16. The sides 15 and 16 are cased, as indicated in Fig. 3, providing space for suitable weights 17, the casing consisting of the usual pulley-piece 18, back-lining 19, and inside and outside boards 20 and 21. The pulley-piece 18 is provided with three longitudinal grooves formed therein for the reception of beads or sash-slides, the outside and inside beads on the right side of the casing being designated as 22 and 23 and the parting-bead as 24. The upper and lower sashes are designated, respectively, as 25 and 26. The beads 23 and 24, however, are not made of solid single strips of wood passing from top to bottom of the casing and nailed thereto, as in the ordinary construction of sash-casing, but they are each formed of an upper solid piece 27, constructed in the ordinary manner and extending to a point something less than one-half the length of the casing below the top thereof, the remainder of the bead being made up of two other pieces—that is to say, a cam-piece 28 and a sliding piece 29—the construction and mode of action of which are as follows: The cam-piece 28 is formed to join the fixed piece 27 abruptly at its upper end 30, but its lower end is provided with an oblique cam-slot 31, the rear face of which is an incline which is prolonged into a tapered or pointed end 32, which merges into the rear side of the groove in which the bead 35 is seated, while the front face of the slot 31 is of dovetailed form and ends abruptly somewhat short of the tapered end 32, as shown at 33. This cam-slot is engaged by an oblique tongue 34 of similar shape and having parallel sides formed upon the upper end of the sliding piece 29, and at the base of the tongue 34 is formed a shoulder 35 of the same width as the end 33 of the piece 28, this shoulder being adapted to abut against said end 33 and 40 to sit flush therewith when the piece 29 is in its uppermost position, as indicated by the dotted lines in Fig. 3. As shown by dotted lines in Fig. 3, the sliding piece 29 has an oblique motion from back to front in an upward direction within its groove in the pulley-piece 18, its upper end being guided by the tongue 34, working in the cam-slot 31, and to provide for a similar guiding of the lower end of the piece 29 the sill of the casing is cut away to form a recess or hole 35^a, having an oblique or inclined forward face 37, corresponding to the motion of the sliding piece 29, which is chamfered, as shown at 36, and to form a guide for the other side of the 45 sliding piece there is an inclined triangular piece 38, secured at the bottom of the groove in the pulley-piece 18 and on which is seated the oblique side 39 of a triangular notch 40, formed on the back of the piece 29, so that 50 by raising the finger-piece 41, pivoted on a transverse pin 41^a in the groove 42 in the face of the sliding piece 29, and by moving the

same upwardly the piece 29 will assume the position shown in dotted lines in Fig. 3—that is to say, it will take its proper place as a 70 sash-slide and the continuation of the bead formed by the pieces 27 and 28, thus holding the window-sash in line—while when the finger-piece 41 is pushed downwardly the sliding piece 29 falls back, so that its front face 75 is flush with the face of the board 18 and is out of the way of the sash-stile, whereby the sash may be turned so as to leave its place in the window-casing.

In the present form of my invention it is 80 intended to have the sash rotatable about one edge thereof in the form of a casement, and to this end I provide on the opposite side of the casing from that containing the movable bead (shown in Fig. 3) hinge-sockets 43 85 and 44, located, respectively, at the upper and lower ends of the sash-stile when the latter is in position ready to be opened. As herein shown, the hinge-socket 43 consists simply of a screw-eye (shown on an enlarged scale in 90 Fig. 7) screwed into the adjacent bead 45 on the left side of the casing, and this is adapted to be engaged by the pintle 46, which is part of a metal stamping 47, bent in the form indicated in Fig. 7 and pivoted upon a screw 48, 95 screwed into the upper end of the stile. This piece 47 is intended to turn about the screw 48 as a pivot, and in order to secure it in position there is provided an arcuate slot 49, through which passes a set-screw 50, which 100 may be tightened to the proper extent to cause the piece 47 to stay in any position in which it is placed, but yet not to be so tightly secured that it may not be easily moved back and forth by the thumb-piece 51. The object of this arrangement is so as to cause the pintle 46 to engage the hinge-socket 43 only when it is desired to open the sash as a casement; but when it is desired to have the sash closed down tight this pintle should be out 105 of engagement with the hinge-socket 43 in order to enable the sash to be pushed down into its proper closed position. It is only the inside sash, of course, of which I am here speaking, for the outside or upper sash has a 110 slightly different arrangement, to be herein-after described.

As it is desirable under ordinary circumstances to have the sash run free of the hinge-socket 43, I generally prefer to have a triangular cam-piece 52 located on the face of the bead 45 immediately above the hinge. This piece has sloping or oblique cam-faces both above and below, as shown, the object of this piece being to engage the edge of the 115 piece 47 and push it back out of the way of the socket 43 in all cases, whether the sash be rising or descending. The other hinge-socket 44 for the inner sash 26 is formed by a simple hole or depression 53 in the sill 14 at a proper 120 point directly beneath the socket 43 and adjacent to the end of the bead 45, this hole being engaged by a bent-wire pintle 54, which 125 is embedded in the lower sash-rail and pro-

jects into the hole 53, thus completing the hinge-joint about which the sash turns. The hole 53 is made sufficiently deep so as not to interfere with the sash being lowered into closed position, although, of course, when the upper hinge-socket 43 is engaged with the pintle 46 the sash is raised sufficiently to allow it to clear the inner sill-board 14^a.

In order to provide for turning the sash about its hinges above described, it is necessary not simply to release it from the bead 23, as hereinabove described, but also to provide for disconnecting it from the weight-cord 55, which passes over the pulley 56 in the pulley-piece 18 and is connected to the weight 17 in the casing. This is provided for by the construction which will now be described. Instead of connecting the cord directly to the sash, as in the ordinary form of counterbalance-hanging, the latter is provided at a point intermediate of its length between the two ends of the right-hand sash-stile with a rectangular notch 57, and this is adapted to engage and hold a projecting lug 58, extending 25 rectangularly from a short cylindrical bar 59, the two together forming the attachment-piece. (More particularly illustrated in Figs. 9, 10, and 11.) The rod 59 is provided at its upper end with an eye 60, through which is 30 passed and knotted the end of the sash-cord 55, while the lower end of the rod 59 extends downwardly a sufficient distance to enable it to be guided in the groove 61, which is formed intermediate between the sash slides 35 or beads 23 and 24 in the pulley-piece 18, and not only the sash-cord but the rod 59 of the attachment-piece is caused to run in this groove, so as entirely to clear the window-sash itself and lie flush with the surface 40 of the pulley-piece 18. The rod 59 is pointed at its lower end 59^a, and at a point intermediate that end and the lug 58 it is formed with a reduced neck 62, having oblique tapered sides 63 and 64 both above and below. 45 This neck portion is destined to be engaged by a latch-piece 65, which is seated in a recess 66 in the pulley-piece just between the groove 61 and the sliding piece 29, and the upper end of this latch is of the same width as the intervening space thus afforded; but the lower 50 end is widened out, so as to give it the sectoral form shown in Figs. 10 and 11. The latch 65 is pivoted upon a screw 67, about which it turns, and it will be seen that the enlarged lower end necessarily lies either to the right or to the left of the narrow parallel strip intervening between the groove 61 and the piece 29, according to circumstances. To receive the right-hand edge 68 of the piece 65, 55 the sliding piece 29 is formed in one side thereof with an oblique tapered notch 69 of the form clearly shown in Fig. 5 and in section in Figs. 10 and 11, and this notch is so positioned that when the sliding piece 29 is in its raised position the notch 69 receives the broadened end 68 of the latch; but when the sliding piece 29 is pushed downwardly the

latch is pushed out of its notch and projects over into the groove 61. The notch 57 in the window-sash is so positioned relatively to the latch 65 as to hold the reduced neck 62 of the attachment-piece directly opposite the lower left-hand corner 70 of the latch 65 when the sash is engaged with the hinge-socket 43 and ready to be turned, and when in this position, therefore, the depression of the sliding piece 29 will cause the latch 65 to be pushed over, so as to engage with the neck 62, and it will be held in this position, so as to lock the attachment-piece and prevent it from being raised. The sash may now be turned upon its hinge without danger of the sash-cord leaving its place; but the tongue or lug 58 will be simply turned slightly about the rod 59 as an axis, so as to allow the lug 58 to pass out of the notch 57. When the sash 26 is turned back into its original position, the notch 57 reengages the lug 58, and the latter is turned back into the position shown in Fig. 11—that is to say, at right angles to the window-casing and fully engaging the notch 57—and upon now raising the sliding piece 29, by means of the finger-piece 41 thereof, the notch 69 is again brought opposite the latch 65, and the oblique side 64 of the neck 62 pushes the latch 65 back into this notch, so that the sash is now again supported through the medium of the sash-cord 55 and weight 17 and may be raised and lowered as desired. The pointed end 59^a is intended to push aside the end 70 of the latch in case the latter falls back, so as to project into the slot 61 after the window-sash has been raised.

Instead of the form of pintle shown in Fig. 7, I may in some cases use a modified form, which is shown in Fig. 12. In this form the pintle 43', which serves the same purpose as the pintle 43, is in the nature of a projection from the circular base-plate 47', which is let into the upper end of the sash-stile, so as to fit flush therewith and turn about a central pivot formed by the screw 48', and this plate 47' may be provided with an arcuate slot 49' and arcuate screw 50', corresponding to the slot 49 and screw 50 in the form shown in Fig. 7.

Having now described the action of the interior or lower sash, that of the upper or outer sash, which differs slightly therefrom, will be readily understood. The modifications applied to this sash are in the nature of simplifications, because the outer sash will not require to be seated against the window-sill to close the window or to be pushed into its lowest position for any other purpose than to be engaged with the hinge-sockets provided therefor and about which it turns. The upper hinge-socket in this case is in the form of a lug 71 upon the attachment-plate 72, screwed to the parting-bead 73 between the two sashes on the left of the casing, and this engages with a pintle 74, fixed rigidly to the upper end of the stile by a plate 75, screwed thereto. It will be of course understood that it is un-

necessary to provide the rotatable pintle shown in Figs. 7 and 8 for the inside sash, because the hinge-socket 71 is at the lowest point of the travel of the pintle 74. The lower 5 hinge of the sash is formed by means of a bent rod 76, embedded in the lower sash-stile and operating in an aperture 77 in the window-sill in precisely the same manner as the rod 54 in the aperture 53. Both sashes are 10 illustrated in position for opening in Fig. 4.

The parting-bead 24 is formed in precisely the same manner as the inner bead 23—that is to say, it is formed of a stationary upper part 78, a cam-piece 79, and a sliding piece 80, all formed exactly the same as the pieces 27, 28, and 29, respectively—and the attachment-piece and latch 81 are likewise precisely similar to those already described for the inner sash. In ordinary cases, however, 15 where the outer sash is made of the same width as the inner sash the former in opening is liable to strike against the projecting tongue 58 of the attachment-piece and turn it about its axis, and to prevent it from 20 impeding the motion of the sash I may provide a suitable recess 82, in which the tongue or lug 58 of the attachment-piece is received. After the outer sash is turned back into 25 position to be closed it will then be necessary before closing the inner sash to push the tongue around slightly into vertical position, so as to cause it to be engaged by the rear side of the notch 57. This, however, may be avoided in several ways—as, for instance, by 30 making the outer sash narrower than the inner sash, so that it clears the tongue 58 without touching it, and in that case the recess 35 82 may be omitted.

While I have shown in the accompanying 40 drawings the preferred form of my invention, it will be understood that I do not limit myself to the precise form shown, for many of the details may be changed in form or position without affecting the operativeness or 45 utility of my invention, and I therefore reserve the right to make such modifications as are included in the scope of the following claims.

Having now described my invention, what 50 I claim as new, and desire to secure by Letters Patent, is—

1. The combination of a window-casing provided with pulley-pieces, sash-beads consisting of a fixed piece and a movable piece, a 55 sash mounted to reciprocate between said beads, the movable piece being slidably mounted in oblique guides on the fixed piece and adapted to be pushed back to free the corresponding edge of the sash, and partible 60 hinges carried by the sash and the window-casing about which the sash is adapted to turn.

2. The combination of a window-casing having sash slides or beads, a sash mounted to reciprocate therein between said slides, counterbalancing means removably attached to 65 said sash and comprising a weight having a

cord passing over a pulley, hinge-halves attached respectively to the casing and sash at one edge of the latter and about which it is 70 adapted to be turned, means for releasing the opposite edge of the sash from its corresponding slide, means for releasing said counterbalancing means from the free end of the sash, and means operated by the movement 75 of the sash-slide to lock said counterbalancing means in position.

3. The combination of a window-casing having slides the inner one of which at one side has a sliding piece adapted to have an oblique reciprocating movement and be pushed back flush with the casing-board, a set of oblique cam-shaped guides confining said sliding piece in its movement, a sash mounted to slide between said slides, and hinge-halves 85 adjacent to one edge of the sash on the opposite side from said sliding piece, whereby the sash is adapted to be released from the slide at one side by pushing said slide up or down and to turn about the hinges at the opposite side.

4. The combination of a window-casing having sash-slides, a sash mounted to slide therebetween, hinge-sockets mounted in the window-casing adjacent to one edge of the sash, 95 pintles carried by the edge of the sash adapted to engage in said sockets, a sliding piece forming a part of one of said sash-slides and adapted to be pushed back flush with the casing, means for counterbalancing said sash, 100 said means being removable from said sash at one side thereof, and means operated by the movement of said sliding piece to lock said counterbalancing means in position.

5. In a combination sash and casing for a 105 window, a sash-slide comprising a fixed piece, a removable piece having an oblique cam-slot therein, and a sliding piece having a tongue adapted to work in said cam-slot and a lower end guided obliquely by suitable guides upon the casing, whereby the raising of said sliding piece will cause it to be moved forward to act as a guide for the sash and the lowering of said sliding piece will cause it to be pushed back flush with the casing.

6. In a combination sash and casing for a window, a sash-slide comprising a fixed piece, a removable piece having an oblique cam-slot therein, and a sliding piece having a tongue adapted to work in said cam-slot and a lower end guided obliquely by suitable guides upon the casing, whereby the raising of said sliding piece will cause it to be moved forward to act as a guide for the sash and the lowering of said sliding piece will cause it to be pushed back flush with the casing, in combination with a second sash-slide, a sash mounted to reciprocate between the two slides, and partible hinges carried by the sash and window-casing to enable it to turn about the 125 opposite edge thereof.

7. In a combination sash and casing for a window, a sash-slide comprising a fixed piece, a removable piece having an oblique cam-slot

therein, and a sliding piece having a tongue adapted to work in said cam-slot and a lower end guided obliquely by suitable guides upon the casing, whereby the raising of said sliding piece will cause it to be moved forward to act as a guide for the sash and the lowering of said sliding piece will cause it to be pushed back flush with the casing, in combination with a second sash-slide, a sash mounted to reciprocate between the two slides, partible hinges carried by the sash and window-casing to enable it to turn about the opposite edge thereof, counterbalancing means consisting of a sash-cord, a pulley over which the cord passes, and a weight attached to the end thereof, and an attachment-piece for removably connecting the sash with said cord comprising a rod sliding in a suitable groove in the casing and having a tongue engaging with a notch in the stile of the sash.

8. In a combination sash and casing for a window, a sash-slide comprising a fixed piece, a removable piece having an oblique cam-slot therein, and a sliding piece having a tongue adapted to work in said cam-slot and a lower end guided obliquely by suitable guides upon the casing, whereby the raising of said sliding piece will cause it to be moved forward to act as a guide for the sash and the lowering of said sliding piece will cause it to be pushed back flush with the casing, in combination with a second sash-slide, a sash mounted to reciprocate between the two slides, partible hinges carried by the sash and window-casing to enable it to turn about the opposite edge thereof, counterbalancing means consisting of a sash-cord, a pulley over which the cord passes, and a weight attached to the end thereof, an attachment-piece for removably connecting the sash with said cord comprising a rod sliding in a suitable groove in the casing and having a tongue engaging with a notch in the stile of the sash, and means operated by the movement of said sliding piece to lock said attachment-piece comprising a pivoted latch adapted to be pushed by means of a cam edge on the sliding piece into engagement with a reduced portion of said attachment-piece.

9. The combination of a window-casing, sash slides or beads attached thereto and one of which has a sliding piece guided to move in an obliquely upward and downward direction, means for raising said sliding piece to a position overlapping the sash and for lowering it to a position clearing the sash, a sash mounted to reciprocate between said slides, hinge-pieces mounted upon the opposite side of the casing adjacent to the sash, co-operating hinge-pieces mounted on the sash and

adapted to engage with said fixed hinge-pieces, counterbalancing means for one side of the sash comprising a sash-cord passing over a pulley and a weight attached at the end thereto, a disconnectible attachment-piece to which the other end of the sash-cord is connected, said attachment-piece having a lug or tongue engaged by a notch in the edge of the sash-stile, and a sector-shaped latch pivotally mounted on the window-casing between said sliding piece and said attachment-piece, said sliding piece having an oblique cam-face adapted to operate said latch to cause it to engage with a reduced portion of said attachment-piece when the sliding piece is pushed downwardly and inwardly, whereby to lock said attachment-piece in position.

10. In a combination window sash and casing, a partible hinge comprising a stationary socket, a pivoted metallic plate carrying a pintle, and an adjusting - screw passing through an arcuate slot in said plate, whereby the same may be tightened to the requisite degree.

11. In a combination sash and casing, hinge means for permitting the sash to be turned about a vertical axis comprising a stationary socket attached to the casing, and a plate pivoted to the sash-stile and having an arcuate slot therein, an adjusting - screw passing through said slot, a pintle carried by said plate and adapted to be engaged by said socket when the plate is in one position and to be out of the way of said socket when the plate is turned to another position, and a thumb-piece projecting from said plate by which the latter may be turned.

12. In a combination sash and casing, hinge means for permitting the sash to be turned about a vertical axis comprising a stationary socket attached to the casing, and a plate pivoted to the sash-stile and having an arcuate slot therein, an adjusting - screw passing through said slot, a pintle carried by said plate and adapted to be engaged by said socket when the plate is in one position and to be out of the way of said socket when the plate is turned to another position, and a double-faced cam-piece attached to the casing of the window and adapted to strike said pivoted plate when the sash is moved past it to push said pintle out of position to be engaged by said socket, substantially as described.

In witness whereof I have hereunto set my hand in the presence of two witnesses.

EDMOND HÉROUX.
